REGULATING SYSTEM

Finn H. Gulliksen and John W. Dawson, Wilkinsburg, Pa., assignors to Westinghouse Electric & Manufacturing Company, East Pittsburgh, Pa., a corporation of Pennsylvania

Application November 3, 1934, Serial No. 751,361

5 Claims. (Cl. 171—119)

Our invention relates to electrical regulators and it has particular relation to electronic tube regulators for maintaining constant the voltage or other characteristic of an electrical machine 5 or circuit.

One object of our invention is to simplify the equipment and control circuits comprised by alternating-current generator voltage regulators of the electronic tube type.

10 Another object of our invention is to increase the reliability of operation and improve the quality of performance of such regulators.

An additional object of our invention is to increase the speed of response of such regulating 15 equipments.

A further object of our invention is to decrease the time required by the regulator to settle disturbances in the regulated quantity.

A still further object of our invention is to minimize interruptions in electronic tube regulator service due to tube failure.

An additional object of our invention is to provide a simple form of load compensation for voltage regulators which are applied to self-excited generators.

25 Our invention itself, together with additional objects and advantages will best be understood through the following description of specific embodiments thereof when taken in conjunction with the accompanying drawings, in which:

30 Figure 1 is a diagrammatic representation of one preferred form of the regulating system of our invention shown as being applied to control the voltage of an alternating current generator;

35 Figs. 2 and 3 are diagrams of curves illustrating certain characteristics of the thermionic detector tubes comprised by the system of Fig. 1;

40 Figs. 4 and 5 are diagrams of curves showing the manner in which the excitation-supply rectifier tubes of the system of Fig. 1 are controlled;

45 Fig. 6 is a diagrammatic representation of one manner in which non-controllable rectifiers may be used in the excitation-supply circuits of the system of Fig. 1;

50 Fig. 7 is a diagrammatic representation of a second embodiment of the regulating system of our invention shown as being applied to control the voltage of an alternating current generator which is provided with a separate exciter.

55 Fig. 8 is a diagram of curves showing the manner in which the excitation-supply rectifier tubes of the system of Fig. 7 are controlled, and

Fig. 9 is a diagram of curves illustrating the 55 superior performance of the delayed-action anti-

5 hunting means comprised by the system of Fig. 7.

Referring to the drawings and particularly to Fig. 1 thereof, the electronic-tube regulating system there depicted is shown as being applied to maintain constant the voltage of an alternating current generator 10 the armature windings 12 of which are connected with a three-phase circuit, represented by conductors 14, and the field winding 16 of which derives its exciting current from one phase of the circuit 14 through a connection which includes a transformer 18, and two sets of rectifier tubes 20 and 22. The effective current passed by these tubes, which preferably are of the grid-controlled gas-filled variety and which are connected in well-known manner to effect full wave rectification, is controlled by a grid-voltage supply circuit which includes one or more detector tubes 36 energized, through transformers 42 and 46, in accordance with the voltage of the regulated circuit 14.

20 Considering first the excitation-supply rectifier tube circuits, during one-half of each cycle of the alternating current voltage which the machine 10 impresses upon the transformer 18, the anode elements 24 of the tubes 20 are subjected, 25 through their connection with the secondary winding 25 of the transformer, to a positive voltage and during the remaining half-cycles the anode elements 26 of the tubes 22 are similarly 30 positively energized. From the cathodes 28 of both sets of tubes one connection is made with the machine field winding 16 through which the rectified current passes and returns, by way of a second connection which includes a switch 67, 35 to the mid-point 27 of transformer winding 25. So far as the normal operation of the system is concerned, only one tube in each of the sets 20 and 22 is essential, the second illustrated tube being for the purpose of minimizing interruptions 40 of regulator service due to tube failure.

45 In order to stabilize the regulating actions and to permit uncontrollable rectifier units, which are less expensive and of longer life, to be used to rectify one-half of the alternating-current wave, we connect the grid elements 32 of the tubes in set 22 only with the machine-voltage error-detecting circuit from which is supplied a potential E_3 for adjusting the magnitude of exciting current supplied to the machine field winding 16 50 by controlling the point in each positive half cycle of anode voltage at which conduction is instituted. The grid elements 30 of the remaining set of tubes 20 are connected, when tubes are used, as in Fig. 1, instead of copper-oxide or 55

other non-controllable rectifiers, shown at 20' in Fig. 6, by means of suitable resistors 31, directly to the tube cathodes, in a manner to render these tubes conductive during substantially the full duration of each positive half cycle of their anode voltage. As will be more completely explained, the inductance characteristics of the machine field winding 16 tend to automatically maintain a substantially equal division of load between the two sets of rectifier units so that, in the illustrated application, our control of the one set only affords practically the same range of adjustment as does the previously employed control of both sets.

15 Considering now the voltage-error detecting circuit of our improved regulating system, in order to eliminate the necessity for a standard potential battery or other equivalent source of reference voltage in these circuits, we prefer to utilize one or more detecting devices 36 in the form of filament-controlled tubes, two of which are shown in the diagram of Fig. 1. The purpose of the illustrated duplication is merely to minimize interruptions of service due to tube failure. Each of these tubes comprises an anode element 44 and a cathode or filament 40 which is supplied, through the transformer 42, with an energizing voltage which varies directly with that of the circuit 14 to be regulated.

20 The tube anode elements 44 have impressed upon them, by means of a transformer 46 which is also energized by the voltage of circuit 14 and in the secondary winding circuit of which a rectifier 48 is connected, a rectified or pulsating uni-directional current. A capacitor 50 and a resistor 51 are connected in parallel across this anode-voltage supply circuit for the detector tubes to partially filter or smooth out the voltage pulsations. The current drawn by 25 these tubes is passed through a resistor 53, the voltage drop E_2 across which thus varies in accordance with the temperature of the tube filaments 40, and a second capacitor 54 connected in parallel with the tubes. This capacitor serves 30 to produce cyclic pulsations of current through the resistor, which pulsations are superimposed upon the average value of the resistor voltage drop.

35 The control potential E_3 impressed upon the excitation-supply tube grids is made up of voltage E_2 and a second component E_1 , in the form of a portion of the relatively constant voltage appearing across the capacitor 50 and the resistor 51, which opposes voltage E_2 . As is indicated by the simplified curves of Fig. 4, this latter voltage is somewhat the greater and hence maintains the grids at an average potential which is negative with respect to the tube cathodes. In Fig. 4 the major reference line 56 applies to the excitation-supply tube cathodes 28, the curve E_2 indicates the voltage impressed upon the anode elements 26 of the tubes 22, and the curve E_1 represents the critical values of negative potential which, when impressed upon 40 the grid elements 32 of the tubes, prevent an institution of tube conduction. No attempt has been made to represent the individual alternating-current ripple components of the two voltages E_1 and E_2 . The major or direct current component of voltage E_2 is controlled by the detector tubes 36 and its alternating-current component is determined by the current drawn by the capacitor 54.

45 To more readily displace the phase position 75 of the ripple in control voltage E_3 from that of

the anode voltage E_2 of the excitation supply tubes by the amount, which, as is shown in Fig. 4, is most advantageous for controlling the conduction starting point of these tubes, we prefer to supply it, as indicated by the diagram of Fig. 1, from a different phase of the circuit 14 than that which supplies the tube anode circuits. It will be understood, however, that, if desired, other expedients may be utilized for accomplishing the same result.

5 The detector tubes 36 are, in the system of Fig. 1, preferably operated at an anode voltage sufficiently high to saturate or place them in a condition in which all of the electrons emitted by the cathodes are attracted to the anodes. In 10 the diagram of curves of Fig. 2, which show the manner in which the current I_p through the tube varies with changes in the anode voltage E_p when different values of energizing voltage E_k are applied to the cathode or filament element, 15 such a saturating voltage E_{p1} is indicated by the dotted line which identifies a region in which changes in the value of anode voltage have little effect upon this tube current. At such a voltage, however, a change in the magnitude of the 20 filament heating voltage from E_{k2} to E_{k1} or E_{k3} effects, as indicated by the wide separation of the curve of Fig. 2, a substantial change in that current.

25 The exceedingly rapid manner in which the 30 tube current is thus caused to vary is indicated by the curve of Fig. 3. Within the voltage range which includes E_{k2} , a high factor of amplification is thus obtained. Such a filament-controlled, 35 detector being essentially a temperature-actuated device, indicates the root-mean-squared value, instead of the average as does an anode-controlled rectifier tube, of the alternating current voltage and thus, in addition to being highly 40 sensitive, provides a character of response which is especially desirable when the generator wave form is subject to deviations or changes.

45 The conversion, by detector tubes 36, of changes in the voltage of the regulated circuit 14 into 45 much larger changes in the direct-current component of voltage E_2 which forms a part of the excitation tube control potential effects a corresponding shift in the position of the axis 60 of this potential E_3 with respect to the tube anode voltage axis 56 and the critical grid voltage curve E_g . By increasing this separation an 50 increase in the regulated voltage delays the point of tube current conduction to reduce the current passed by the tubes 22, and, by decreasing this separation, a decrease in the regulated voltage 55 similarly initiates conduction at an earlier point in each positive half cycle of tube anode voltage to thereby increase the effective current passed by these tubes.

60 As before pointed out, such adjustments are 60 accompanied by comparable changes in the effective current passed by the opposition connected rectifiers 20 even though these tubes are conductive throughout their entire corresponding half cycles of anode voltage; as indicated by the 65 shaded area 64 of Fig. 5. This substantially equal division of current results from the predominating inductance characteristics of the machine field winding 16 in which changes in current during succeeding half cycles of energizing 70 voltage are balanced by action of the energy stored in the magnetic field surrounding the winding. This field of energy causes to be set up counter-electro-motive forces which oppose the 75 passage of current through the continuously con-

ducting tubes 20. Control of the exciting current supplied to machine winding 16 is thus as satisfactorily effected as were the rectifier units 20 (Fig. 1) or 20' (Fig. 6) also to be influenced by a regulated quantity responsive control voltage, an arrangement which would require a doubling of the minimum permissible current capacity of the detector output circuit and which further would not permit non-controllable units (20') to be employed.

In placing the complete regulating system shown in Fig. 1 into operation, the regulated generator 10 is excited, during its starting period, from a separate source of direct current, indicated 15 in the form of a battery 65, which may be connected to the field winding 16 by shifting the transfer switch blade 67 to its upper position. As soon as the generator voltage has reached its substantially normal value, switch 67 is returned 20 to the lower position illustrated in which the field winding 16 is connected for self-excitation through the rectifier tubes comprised by our improved regulating system.

In operation of the system, as long as the magnitude 25 of the voltage supplied by the generator to the regulated circuit 14 is of the normal or desired value, the filaments of the detector tubes 36 are heated to an intermediate temperature and the control voltage impressed upon the grids of 30 the excitation-supply tubes is of such character that they supply to the generator field winding that value of exciting current which maintains the generator voltage at this desired value.

Upon the occasion of a decrease in this regulated voltage, the voltage impressed upon the detector filaments correspondingly decreases and the tubes pass a smaller value of anode current. The resulting lowering of this current correspondingly so modifies the rectifier tube control potential 40 as to raise the value of exciting current supplied to the machine field winding and restore the voltage of machine 10 back to its desired value.

In a similar manner, upon the occasion of a rise in the voltage of the regulated circuit 14, 45 the temperature of the detector filaments is increased, and these detectors draw more current. This so modifies the control voltage E_3 as to lower the existing current and restore the voltage of machine 10 back to its desired value.

The value of voltage which the regulator will maintain may be changed by adjusting the position of a tap connection 55 along the detector-circuit resistor 53. Such an adjustment varies 50 the value of the control potential component E_4 and thereby requires that the detector filament operate at correspondingly changed temperatures to maintain their control of the excitation-supply tubes.

By duplicating the detector tubes 36, we have 60 found that interruptions in service due to tube failure may be greatly minimized. In the filament supply circuit of these parallel connected devices we connect a resistor 68 which functions to so increase the voltage across the filament of one tube in case of failure of the other as to cause this remaining operative tube to continue to maintain the regulated voltage at its normal value. To produce this desired effect the resistor must of course be rather closely adjusted in resistance value.

A similar duplication of tubes in each of the excitation-supply rectifier sets 20 and 22 also minimizes interruption of service due to tube failure, inasmuch as an inoperative condition of one 75 of the tubes in each or both of these sets is

found not to detrimentally effect regulator operation, the change in excitation supply circuit impedance being compensated for by a readjustment which the detector circuits automatically make in the character of the control voltage E_3 .

We have discovered that the system just described is inherently stable in operation and exhibits no tendency to hunt or overshoot in its corrective actions. We believe that such stability is the result of the before-discussed inductive balancing action between the two sets of excitation-supply rectifier units when taken in combination with the action of the ripple-amplifying capacitor 54 in the control voltage supply circuit. This capacitor appears to introduce a slight delay in the attainment by the detector tube circuit of its final or newly adjusted condition upon a change in filament temperature. In any case, the regulator of Fig. 1 exhibits a high degree of stability. It further has a much higher speed of response and requires very much less time to settle disturbances in the regulated voltage than do previously known systems of comparable character. Upon actual test, sensitiveness of regulation approaching one-tenth of one percent were observed upon varying the load of the regulated generator from zero to 125 percent of its rated capacity.

Considering now the modification of our invention depicted by Fig. 7, the regulating system there shown controls the voltage of an alternating-current generator 10 which has its field winding 16 energized by means of a separate generator or exciter 70. The exciter field winding 71 is supplied with a unidirectional energizing current from the generator output circuit 14 through a connection which includes a transformer 18' and a pair of rectifiers, in the form of grid-controlled gas-filled electronic tubes 72 and 74, which are connected to effect full wave rectification.

The grid elements 75 of these tubes have impressed upon them a direct current control voltage E_1 which is supplied through a circuit which includes a two-element detector tube 36, the cathode or filament 40 of which is energized by a voltage E_2 derived from the regulated circuit 14 through a transformer 42 as in the system of Fig. 1. The anode element 44 of the tube has impressed thereon a uni-directional potential supplied also from the regulated circuit through a transformer 18 and a full wave rectifier 19. Between the rectifier and the detector tube, filtering apparatus, in the form of a capacitor 80 and a resistor 82, is disposed in well known manner.

As in the case of the system of Fig. 1, the excitation-supply rectifier tube control voltage is made up of two components, E_4 , which comprises the drop across a portion of the resistor 82 and which tends to make the tube grids positive, and E_5 , which comprises the voltage drop across a resistor 83 through which the current drawn by the detector tube 36 passes and the polarity of which opposes that of component E_4 and tends to make the tube grids negative. Both voltages E_4 and E_5 contain small alternating-current ripples no attempt to represent which has been made in Fig. 8.

During normal operation of the regulating system the magnitude of component E_5 slightly exceeds that of E_4 thereby making the sum E_6 a relatively small value of unidirectional voltage which renders the grid elements 75 of the rectifier tubes negative. Except during periods of exciter field current change when, as will be further ex-

plained, there is set up in an anti-hunting resistor 85 a stabilizing potential E_s , the voltage E_7 impressed upon the tube grids is the same as the detector circuit output voltage E_6 .

The operation of the system of Fig. 7 simulates that of a vibratory contact type of regulator in that adjustment in the current supplied to exciter field winding 71 may under certain conditions be effected by rendering the rectifier tubes 72 and 74 alternately completely conductive and completely non-conductive, the relative values or ratio of these conducting and non-conducting periods being varied in such manner as to maintain the voltage of machine 10 at its desired value. The manner in which the illustrated circuits effect such operation will be understood by reference to Fig. 8, in which curve E_a represents the wave of anode voltage impressed upon each of the rectifier tubes and curve E_g the critical grid voltage necessary to maintain the tube in a non-conductive state.

When the voltage of regulated circuit 14 is of the normally desired value, the grid control potential E_7 varies, as indicated in Fig. 8, between two limits such as are indicated by the parallel lines 87 and 88, this variation resulting from correspondingly slight fluctuations in the detector filament heating voltage which each conducting and non-conducting period of the rectifier tubes 72 and 74 causes. When this control potential is of the value 87, conduction starts at an early point in each positive half cycle of the anode voltage of the rectifier tubes and continues during the remainder of that half cycle as is indicated by the shaded area 91 in Fig. 8. However, when, as a result of such conduction, control voltage E_7 has been shifted to the value indicated by line 88, the rectifier tubes are prevented from becoming so completely conductive.

In practice, the presence of the before-mentioned alternating-current ripples in the control potential E_7 somewhat modifies the described action in that these ripples introduce a combined magnitude and phase-shift control effect which varies the conductivity of the excitation-supply tubes without necessitating the extreme "on and off" action except for large regulated voltage variations.

Hence, when the voltage of circuit 14 is of the normal or desired value, the tube conductivity characteristics are automatically maintained such as to cause exciter 10 to supply to field winding 16 of machine 10 the proper exciting voltage to keep the machine voltage at this desired value.

Upon the occasion of a drop in the voltage of regulated circuit 14, the average temperature of the filament 40 of the detector tube 86 is correspondingly lowered, so that the tube draws less current through resistor 83 and thus reduces the magnitude of control-potential component E_s . This makes the grid control voltage E_7 less negative with the result that the ratio of the conductive to non-conductive periods of rectifier tube operation, when the control variation is this extreme, is correspondingly raised, the amount being sufficient to restore the machine voltage back to its desired value.

In a similar manner, a rise in the regulated voltage increases the average temperature of the detector filament which, in turn, raises the magnitude of component E_s and renders the grid control voltage E_7 more negative. This, in turn, decreases the ratio of conducting to non-conducting periods, when the control variation is this extreme, of the excitation supply tubes and lowers

the voltage of machine 10 by an amount appropriate to restore it to the desired value.

The value of voltage which the regulator will maintain may be changed by adjusting the position of a tap connection 84 along the detector-circuit resistor 83. Such an adjustment varies the value of the control potential component E_s and thereby requires that the detector filament operate at correspondingly changed temperatures to maintain its control of the excitation-supply tubes.

In the system of Fig. 7, which is more completely described and claimed in our copending application Serial No. 751,362, filed November 3, 1934, and assigned to the same assignee as this invention, we have also disclosed a highly improved form of stabilizing or anti-hunting means which prevents overshooting of the corrective actions without substantially detracting from the speed of response of the regulating system. These means comprise the before mentioned resistor 85 connected in the grid control circuit of the excitation supply tubes which resistor is connected in series with a capacitor 92. The series-connected resistor and capacitor are, in turn, energized by the voltage appearing across a second capacitor 94 which together with a series connected resistor 86 is directly influenced by the voltage appearing across the field winding 11 of the machine excitor 10.

The manner of operation of these anti-hunting means may be best explained by reference to the curves of Fig. 9 which are drawn to illustrate the action resulting from a sudden drop in the regulated voltage E_k which takes place at time t_1 . Upon the occasion of this drop, the regulating system just explained functions to increase the current supplied to and hence the voltage appearing across the exciter field winding 71. As a result, there is drawn through the resistor 85 a current which acts to charge capacitor 94 to a value of potential higher than that previously existing. The general manner in which this increase takes place is indicated by curve 97 of Fig. 9. It will be noted from this curve that there is an appreciable delay before the capacitor attains the new value of charge corresponding to the raised exciter field voltage.

As this voltage across capacitor 94 rises, it causes to be forced through the resistor 86 a current which charges capacitor 92, this current causing to appear across the resistor a stabilizing voltage E_s which varies in the general manner indicated by curve 98 of Fig. 9. The polarity of this voltage is such as to oppose or retard the corrective action instituted by the regulator. In the specific instance under course of explanation, it combines with the voltage E_k to make the control potential E_7 of a greater negative value and thereby so prematurely decreases the effective conductivity of the rectifier tubes 72 and 74 as to prevent the regulator initiated increase in machine excitation from being continued until the regulated voltage is raised above the desired value.

Upon the occasion of an increase in the regulated voltage and a corresponding reduction in the exciting current supplied through the rectifier tubes, an action exactly similar to that above explained takes place, with the exception that the capacitors 94 and 92 force discharging currents through their associated resistors and the control voltage E_7 is made of a lesser negative value than E_s to thereby appropriately arrest the corrective action. In both instances, how-

ever, this retarding force does not come into effect until an appreciable time after the corrective action has been instituted, with the result that the regulator is much quicker in settling the disturbed quantity than were the anti-hunting influence to be directly proportional to the magnitude of the corrective action, as in comparable anti-hunting systems developed in the past. The performance of one such comparable system is indicated by the dotted sections of the curves of Fig. 9, which show the undesirable retarding effect on regulating action which such comparable systems have exerted.

These prior art systems introduce, as shown by curve section 98, a corrective-action retarding potential which is directly proportional to the rate of change of the correction and which thus seriously slows it down, as shown by curve section 99. In our improved anti-hunting system, however, the regulator is left substantially unhampered until some appreciable later time, represented by the peak of the curve E_s, when the maximum retarding influence is first exerted. Substantial benefits in regulator response are in this manner made possible.

The tube duplication expedients of the system of Fig. 1 are also applicable to the regulator of Fig. 7 for the purpose of minimizing interruptions in service due to tube failure.

We have found that the described regulating systems may be given a rising characteristic with machine load increase by inserting in the excitation and detector-tube supply circuit a resistor, as shown in Fig. 7 at 90, in which a voltage drop proportional to the machine exciting current is set up. Since as the load on the regulated machine is increased greater excitation is required to maintain the voltage at a substantially constant value, this resistor causes the voltage of circuit 14 to be maintained above that impressed upon transformer 42, which latter voltage the regulator keeps constant, by an amount proportional to the machine load. The magnitude of this resulting rising characteristic may be raised by increasing the resistance of the compensating resistor 90 and lowered by decreasing the value of this resistance.

Although we have shown and described certain specific embodiments of our invention, we are fully aware that many modifications thereof are possible. Our invention, therefore, is not to be restricted except insofar as is necessitated by the prior art and by the scope of the appended claims.

We claim as our invention:

1. Regulating apparatus for an alternating-current dynamo-electric machine comprising a circuit for supplying an exciting current to the machine, a grid-controlled rectifier tube for adjusting the magnitude of said current, a detector tube having an anode and a filamentary cathode, a circuit energized by the voltage of said machine and including a rectifier and an impedor for impressing a unidirectional potential between

the elements of said detector tube, means for energizing said cathode by a current determined by a characteristic of the machine to be maintained constant, and means for impressing the voltage drop across said impedor upon the grid of said grid-controlled tube. 5

2. Regulating apparatus for an alternating-current dynamo-electric machine comprising a circuit for supplying an exciting current to the machine, a grid-controlled rectifier tube for adjusting the magnitude of said current, a detector tube having an anode and a filamentary cathode, a circuit energized by the voltage of said machine and including a rectifier and an impedor for impressing a unidirectional potential between 10 the elements of said detector tube, means for energizing said cathode by a current determined by a characteristic of the machine to be maintained constant, means for impressing the voltage drop across said impedor upon the grid of 15 said grid-controlled tube, and a capacitor connected in parallel-circuit relation with the detector tube to stabilize regulatory actions.

3. In a regulating system comprising a plurality of parallel-connected detector tubes each 25 of which has an anode and a filamentary cathode, a circuit for supplying to all of said cathodes a common energizing voltage which varies in accordance with the regulated quantity, and a quantity-control circuit through which the anode 30 currents of all of said tubes flow, the combination of an impedor connected in series with said cathode-energizing circuit to raise the voltage applied to the remaining tube cathodes in the event of failure of one or more of them. 35

4. In a regulating system comprising a pair of parallel-connected detector tubes of the filament-controlled type, a circuit for supplying to both of said tubes a common filament-heating voltage, which varies in accordance with the regulated 40 quantity, and a quantity-control circuit energized by the combined current passed by said two tubes, the combination of an impedor connected in series with said cathode-energizing circuit, said impedor functioning, in the event that 45 one tube fails, to raise the filament-heating voltage applied to the remaining tube by an amount sufficient to compensate for the loss of current in the quantity-control circuit due to such failure.

5. In a system comprising an electrical generator having a field winding, a circuit through which the generator supplies exciting current to said winding, and a regulator energized by the voltage of the generator through a circuit a portion of which is common with the exciting- 50 current supply circuit and adapted to so adjust said exciting current as to control the generator voltage, the combination of load-compensating means for the regulator comprising an impedor 55 serially connected in the common portion of the field current and regulator supply circuits. 60
